UNITED STATES PATENT OFFICE.

MAURICE J. ROCHE, OF NEW YORK, N. Y.

VESTIBULE-CURTAIN COUPLING.

1,267,272.

Specification of Letters Patent. Patented May 21, 1918.

Application filed August 28, 1917. Serial No. 188,659.

To all whom it may concern:

Be it known that I, MAURICE J. ROCHE, a citizen of the United States, and a resident of city of New York, Elmhurst, borough of 5 Queens, in the county of Queens and State of New York, have invented a new and Improved Vestibule-Curtain Coupling, of which the following is a full, clear, and exact description.

10 This invention relates to curtain holders and particularly to an improved construction for coupling the curtains used on vestibules of railway coaches, and has for an object the provision of an improved structure 15 which holds the curtain in proper position, but will automatically become disengaged when a predetermined strain has been brought to bear thereon.

Another object in view is to provide a coupler for vestibule curtains arranged with parts thereof on the curtain and part on the next vestibule, said parts being interlocking and adjustable, so as to automatically become released at any desired pull.

25 A still further object of the invention is to provide a coupler for vestibule curtains having a head or knob with pivotally mounted jaws engaging the same, and a sleeve holding the jaws in position until the cars 30 have separated and pulled the head to a position outside of the sleeve.

In the accompanying drawing:

Figure 1 is a longitudinal, fragmentary, sectional view through the abutting vestibules of two adjacent cars, an embodiment of the invention being shown in connection therewith.

Fig. 2 is an enlarged side view of the coupler shown in Fig. 1, certain parts being 40 broken away on approximately line 2—2 of Fig. 3.

Fig. 3 is a top plan view of the coupler shown in Fig. 2, one of the curtain rods being shown in connection therewith.

45 Fig. 4 is a horizontal longitudinal sectional view through the structure shown in Fig. 3.

Fig. 5 is a detail fragmentary sectional view through Fig. 2 on line 5—5.

50 Fig. 6 is a sectional view through Fig. 2 on line 6—6.

Fig. 7 is an enlarged detail fragmentary sectional view showing a different position

of the coupling members to that shown in Fig. 2.

55

Referring to the accompanying drawings by numerals 1 and 2 indicate coaches of any desired kind provided with vestibules, car 2 having a curtain 3 mounted thereon and carrying part of the coupler 4, while car 1 carries the remaining part. The curtains 3 are usually wound on spring rollers which automatically wind up the curtain whenever the curtain is released. If the edge of the curtain was connected by a hook or otherwise 60 more or less rigidly to car 1 and the two cars should separate curtain 3 would unroll to its full length and would then be torn. The coupler 4 is intended to take care of accidents of this kind and to automatically open when a predetermined tension has been brought to bear thereon, as for instance, when the cars are separated there is an extra pull on curtain 3. As hereinafter described 65 the parts of the coupler 4 are made so as to be easily adjusted in order that any desired pull may be required before the coupler opens. As shown in Fig. 4 the coupler consists of parts 5 and 6, part 5 being connected to curtain 3 while part 6 is connected to the 70 car 1. Part 6 is provided with posts 7 screwed or otherwise rigidly secured to the car 1, said posts carrying a bar or pin 8 which extends through jaws 13 and 14 and acts as a pintle therefor. Jaw 13 is provided 75 with apertured bosses or sleeves 10 which are formed with pressed out ears carrying rollers 11, whereby as either car moves up and down the parts may freely slide without any tendency of the bar 8 binding. Jaw 13 is 80 preferably provided with an extension 15 formed with a hook 16 which may be turned around and hooked on curtain bar 17 as shown in Fig. 7 if desired and whenever part 5 is in position on curtain 3. It is of 85 course, understood when arranged in this manner, namely as shown in Fig. 7, the curtain will become torn in case the cars are pulled apart. The jaws 13 and 14 are each provided with a recess 18 which form a conical shaped socket when the jaws are together 90 so as to fit over a conical shaped head 19 on the rod 20. The rod 20 passes loosely through the guide 21 which is screwed or otherwise rigidly secured to the casing 22, 95 and in addition passes through the spring 100

105

23 so that the nut 24 may be threaded thereon for varying the tension of spring 23. A variation in the tension of spring 23 will vary the necessary pull to separate the jaws 5 13 and 14 from the head 19. Casing 22 is formed integral with or rigidly secured to clamping base 25 which is riveted or otherwise secured to curtain 3. The base 25 is provided with members 26 and 27 which 10 have secured to their outer ends bars 28 and 29 as shown in Fig. 2 which bars are also supported by brackets 30 and 31 secured to curtain 3. By this construction and arrangement if the car is not provided with 15 part 6 the hook or other securing means connected with the car may be interlocked with either of the bars 28 and 29 for holding the curtain in proper position. Surrounding the casing 22 is a shell or sleeve 33 which has 20 an up-standing annular flange 32 fitting in the brackets 26 and 27 as shown in Fig. 5. Springs 34 and 35 are arranged below the up-standing flange 32 so as to continually urge the parts in the sleeve 33 outwardly to 25 the position shown in Fig. 2. When in this position the sleeve 33 surrounds and snugly fits the jaws 13 and 14 so as to hold the same in engagement with the head 19. This engagement will remain until the head 19 30 and associate parts have been pulled outwardly against the action of spring 23 to the position shown in Fig. 4 whereupon the jaws 13 and 14 will separate and then release the head 19 and associate parts including 35 curtain 3. In order to lock the sleeve 33 in its outer position one or more bayonet slots 36 are provided in sleeve 33 through which pin 37 projects. When the parts are in the 40 position shown in Figs. 3 and 4 the sleeve is locked in its outer position, which position is secured by manually rotating the sleeve 33 after it has been moved to its outer position. If it should be desired to uncouple the device at any time the parts 45 may be pulled apart if the operator so desires, but preferably sleeve 33 is moved back until the end is flush with the outer face of the guiding member 21 whereupon the jaws will move apart under a slight pull. A reverse movement will also close the coupling, 50 namely a movement of the jaws in such a direction as to close the head 19 after sleeve has been moved through the casing 22 against the action of springs 32. After the jaws 55 have been placed in position the sleeve is forced to slide thereover and then turned to the locking position shown in Fig. 3. In order that the jaws 13 and 14 may normally remain together a spring 38 is provided acting against the extension 15 against a lock 39 on jaw 14, spring 38 being comparatively small and is intended normally to hold the jaws together lightly. By this arrangement of coupler it will be unnecessary for the 60 trainmen in uncoupling the cars to bother 65

with the curtain, as the curtain will automatically uncouple itself after the proper strain has been brought to bear on the coupler. This will not only save work, but it will also prevent tearing of the curtain when 70 the trainmen forget to uncouple the same.

What I claim is:

1. A coupler of the character described, comprising a pair of pivotally mounted jaws having a socket therein, a head fitting into 75 said socket, a sleeve normally surrounding said jaws, a resilient member for normally holding said sleeve over said jaws and said head, means for connecting said head to a curtain, and means for connecting said jaws 80 to a support.

2. A vestibule curtain coupler comprising a base, a casing connecting with said base, a guide arranged in said casing, a post on opposite sides of said casing, a coupler head 85 provided with a rod extending through said guide, an adjustable nut arranged on said rod, a spring surrounding the rod positioned between the nut and guide, a pair of pivotally mounted jaws adapted to surround said 90 head, a sleeve slidably mounted on said casing and normally arranged to overlap said head so as to hold the jaws in engagement therewith, a plurality of springs arranged between said posts and said casing for normally holding said sleeve so as to overlap said head and said jaws, and means connecting said jaws to a support, the arrangement of the sleeves, jaws and head being such that the parts will be connected until a pull on the jaws and head overcome said spring and the jaws move out from said sleeve.

3. A coupler of the character described comprising a pair of pivotally mounted jaws having a socket formed with beveled walls, 105 a casing, a head having beveled walls fitting the walls of said socket, a rod connected with said head extending into said casing, a spring acting on said rod for normally holding said head adjacent said casing, and a sleeve carried by said casing normally surrounding said head and said jaws, said jaws and said head being capable of movement against the action of said spring whereby said jaws will become released.

4. A coupler of the character described comprising a pair of jaws having a socket, a head fitting in said socket, a casing, means movable in said casing and connected with said head, a spring in said casing engaging said means for normally holding the head adjacent said casing, a sleeve slidably mounted on said casing normally overlapping said head and said jaws, said sleeve being provided with upstanding flange, and a spring engaging said upstanding flange for continually urging the sleeve to move in one direction.

5. A coupler of the character described comprising a base, a pair of channelled up-

- rights extending from the base, a casing extending from said base between said uprights, a sleeve surrounding said casing, said sleeve being formed with a flange, a spring 5 arranged in the channel part of each of said uprights engaging the base and the flange for urging the sleeve to move toward the outer end of said casing, a reciprocating member arranged in said casing, a spring 10 acting on said reciprocating member holding same resiliently against movement, a head connected with said reciprocating member and positioned normally in the outer end of said sleeve when the sleeve is in its 15 outer position, a pair of pivotally mounted jaws surrounding said head and positioned in the sleeve, said jaws substantially filling the end of said sleeve so that they cannot move away from the head until moved to a position beyond the sleeve against action of 20 said spring, and means for connecting said jaws to a support.
6. A coupler of the character described comprising a two-part automatic coupling mechanism formed so as to become automatically 25 disengaged when a predetermined pull is exerted thereon, a pair of bars arranged adjacent one of the parts of the coupler and a hook member connected with the other part of the coupler whereby the coupler only 30 may be used when mating parts are present and the hook member may be used when mating parts are absent.
